UNITED STATES PATENT OFFICE.

JESSE CONWAY, OF BALTIMORE, MARYLAND, ASSIGNOR OF ONE-HALF TO
JOHN N. CONWAY, OF SAME PLACE.

FEED-BAG.

SPECIFICATION forming part of Letters Patent No. 314,915, dated March 31, 1885.

Application filed October 15, 1884. (No model.)

To all whom it may concern:

Be it known that I, JESSE CONWAY, a citizen of the United States, residing at Baltimore, in the State of Maryland, have invented certain new and useful Improvements in Feed-Bags, of which the following is a specification.

My invention relates to an improved feed-bag for feeding horses while harnessed to a vehicle.

10 The object of my invention is to provide a bag or receptacle with such means for its support in front of the animal as will leave the latter's head perfectly free for movement.

15 The construction of the improved feed-bag whereby the desired result is accomplished will be described in connection with the accompanying drawings, which illustrate what is deemed the best means of carrying the invention into effect.

20 Figure 1 is a side view showing the feed-bag supported in front of an animal. Fig. 2 is a top view of the feed-bag open, with its cover turned to the position it takes when assisting to support the bag. Fig. 3 is a top 25 view of the bag, and indicating by broken lines the movement which the cover has. Fig. 4 is a side view of the bag closed. Figs. 5 and 6 are views of parts of the swivel which connects the cover and bag.

30 The letter A designates the feed bag or receptacle, which may be made of any suitable material. About the top rim of this bag or receptacle is secured a metal rod the two ends b of which are near together and project laterally. When the receptacle consists of textile material or leather, the rod, in the form of a hoop, may be secured thereto by turning the top edge of the material over the hoop and stitching it. The cover C must have a shape 35 to conform to the receptacle. In the present instance it is circular. About the rim of the cover another rod is secured, substantially like that on the receptacle. The two ends d of this rod also project laterally. A swivel-connection whereby the cover is attached to the receptacle consists of two disks, e and e', pivoted together at their centers. The disks each have a flat face, f, which are in contact, and a central hole, g, for a rivet, g', which pivots 40 them together. Each disk also has on its flat face two grooves, h, deep enough to receive

the ends of the metal rods. The grooves of the lower disk, e, are occupied by the projecting ends b of the rod on the receptacle, and those of the upper disk, e', by the ends d of the rod on the cover. The rods may be secured in the grooves by any suitable means. The two disks having the ends of the rods in them are then riveted together. By this swivel-connection the cover turns on its pivot g' in a horizontal plane, as shown. The two rods near together are exposed between the disks and the receptacle and cover, and said exposed parts constitute a sort of shank. The upper disk, e', has another groove, k, extending in a direction crosswise of the diverging grooves, and a wire loop, l, has its ends in this groove, and is free to turn. This wire loop is bent to form the angles n, (see Fig. 4,) and serves as a fastener to keep the cover in the position it must have (see Fig. 2) when assisting as a brace to support the bag. When the cover is in this position, the loop l is directly above the exposed ends or shanks b of the rod on the receptacle, and the loop may then be pressed down, so as to embrace the said shanks by bringing the angles n on opposite sides of the shanks. Thus placed the loop acts as a fastener to make the brace rigid and prevents the cover from turning. Two straps, p, are secured to the cover on the side opposite the swivel, and serve to attach the cover to the horse-collar, as shown in Fig. 1. When the cover is thus attached to the collar, and the swivel is made rigid by the loop-fastener, the cover will serve as a brace to project the feed bag or receptacle A in front of the animal's breast, as in Fig. 1. A hanger-cord, q, has one end attached at each side q' of the bag or receptacle. This cord may be thrown over the animal's head and engaged back of the hames r; or another cord, s, may be attached to the cord q, and said cord s engaged on the check-rein hook t. Either place of engaging the hanger-cord will serve the purpose of suspending the bag or receptacle, and leave the animal's head perfectly free to move, and consequently free to eat comfortably. The cover is provided with straps u, and the bag with buckles v, whereby to secure the cover when the bag is full.

I have referred to the feed-bag as a "bag or

receptacle." By this I mean that a "bag" in the strict meaning of the term is not essential. A box with rigid sides may be employed and, likewise, a rigid cover.

5 Instead of the two straps *p* on the cover a hook or clamp may be used to attach the cover to the collar.

Having described my invention, I claim and desire to secure by Letters Patent of the United States—

15 1. The combination, with the feed-bag and cover, each having a rod with two ends projecting laterally, of two disks centrally pivoted together, each having a flat face, *f*, one in contact with the other, and both flat faces provided with two grooves, *h*, which are occupied by the said laterally-projecting rod ends, as set forth.

20 2. A feed-bag having secured to its top rim a rod whose two ends, *b*, are brought near together, project laterally, and are attached to a disk, *e*, a cover having a rod with two laterally-projecting ends, *d*, attached to a second disk, *e'*, a pivot, *g'*, connecting the said two disks, whereby the cover may turn in a horizontal plane, and a loop-fastening device at-

tached to the upper or cover disk, *e'*, and having two angles, *n*, which may embrace the projecting rod ends *b* of the bag, the parts being combined as set forth.

3. A feed-bag provided with a hanger-cord for engagement back of the hames, and having secured to its top rim a rod whose two ends, *b*, are brought near together, project laterally, and are attached to a disk, *e*, a cover provided with straps for attachment to the harness-collar, and having a rod with two laterally-projecting ends, *d*, attached to a second disk, *e'*, a pivot, *g'*, connecting the said two disks, whereby the cover may turn in a horizontal plane, and a loop-fastening device attached to the upper or cover disk, *e'*, and having two angles, *n*, which may embrace the projecting rod ends *b* of the bag, the parts being combined as set forth.

35 40 45 In testimony whereof I affix my signature in presence of two witnesses.

JESSE CONWAY.
